UNITED STATES PATENT OFFICE.

CHARLES PUDDEFOOT, OF DETROIT, MICHIGAN.

DESIGN FOR A CORKSCREW.

SPECIFICATION forming part of Design No. 21,761, dated August 9, 1892.
Application filed May 12, 1892. Serial No. 432,789. Term of patent 7 years.

To all whom it may concern:

Be it known that I, CHARLES PUDDEFOOT, a citizen of the United States, residing at Detroit, in the county of Wayne and State of Michigan, have invented and produced a new and original Design for Corkscrews, of which the following is a specification, reference being had to the accompanying drawings, forming a part thereof.

Figure 1 is a plan view of my corkscrew.

Fig. 2 is a side elevation thereof.
This design consists of a yoke-shaped handle with flat-sided extensions B, which have upwardly-curved portions C, formed with a

circular recess D, the side extensions and upwardly-curved portions being of the same width, thereby forming a substantially V-shaped open space below the same, all as shown.

What I claim as new, and desire to secure by Letters Patent, is—

The design for a corkscrew, as herein shown and described.

CHARLES PUDDEFOOT.
